DEVICE FOR FORMING FABRICATIONS
FROM STRIP MATERIAL

Harry Fuchs, New York, N. Y.

Application October 21, 1949, Serial No. 122,719

11 Claims. (Cl. 112—23)

1

My invention relates to a device for forming fabrications from strip materials of various kinds. It is intended for use with a joining device adapted to join strip material edge to edge, such for example as a sewing machine, and it will be understood that any other kind of joining device may be used.

One object of my invention is to provide an attachment for use with a household sewing machine whereby a woman can make her own hats, handbags, as well as other articles, out of straw braid, felted strip, or fabric strip cut on a bias and folded double to simulate straw braid, thereby effecting considerable economy in the cost of her wardrobe, and savings in household expenditures.

Another object of my invention is to provide an attachment for use with straw braid sewing machines in hat factories and millinery workrooms for automatically holding and controlling a forming strip material fabrication whereby relatively inexperienced persons can make strip material fabrications which heretofore have required the skill of highly experienced operators, and thereby provide for the expansion of the American straw braid hat industry and the export of American straw braid hats to foreign countries.

Further objects of the invention will appear hereinafter.

My invention accordingly consists in the method, system, combinations of elements, arrangements of parts, and in the several steps and relation and order of each of the same to one or more of the others, as will be disclosed herein. The many novel features embraced in this invention are far-reaching in their scope and are applicable in many embodiments other than that described, and I therefore do not wish to be limited except as indicated in the appended claims and within the doctrine of equivalent.

Referring to the accompanying drawing which illustrates one embodiment of my invention as an example, 1 indicates a supporting plate which is adapted to be secured to the bed plate of a sewing machine by a thumb screw passing through the hole 2. The offset 3 shown in dotted outline is adapted to fit in a slot in the throat plate of the sewing machine and is inserted therein prior to the insertion of a thumbscrew in hole 2.

The supporting plate 1 is now aligned for use with the sewing machine, of which 4 indicates the presser foot, 5 the needle, and 6 the gage forming part of the presser foot and adapted to maintain the edge of the forming fabrication in line for the needle 5.

2

Attached to plate 1 by means of the rivets or screws 7 and 8, are supports 9 and 10 which function as a guiding element. Each of the supports 9 and 10 has at the sides thereof grooves 5 (not shown because well understood by those skilled in the art), in which are adapted to slide the legs of the U-shaped longitudinally extensive element or component 11 having a bend 12 at one end for manual manipulation, and an angular offset 13 secured to the other end by suitable means as for instance by spot welding. The element or component 11 slides in the grooves of the supports 9 and 10 transversely of the line of feed with respect to the presser foot 4 and needle 5. 15 It will be noted that leftward of the line of feed toward the needle, the component 11 moves transversely of the line of feed at an obtuse angle exceeding 90° and this important feature helps prevent the periphery of the forming fabrication 20 from running off the gage 6.

14 indicates a needle or equivalent nucleus-holding element, upon which is impaled or secured a nucleus such as the disc 15 shown in fragmentary view. The disc 15 may be of buckram, cardboard, or other suitable material.

In its initial position, after it is impaled upon the needle 14 the periphery of the disc 15 rests against the gage 6 of the joining device, and as the unformed strip material 16 is fed to the joining device, successive sections of the strip material are spiralled upon the nucleus 15 thus forming the fabrication indicated in fragmentary view by 17. The unformed strip material 16 passes through the guide 18 secured to plate 1 and is held in proper alignment for joinder to the nucleus and the forming fabrication by the adjustable gage 19 held in place by the thumb screw 20 which screws into plate 1.

As successive sections of strip material are joined to the nucleus by the joining device and the fabrication 17 becomes progressively larger, the component 11 slides leftwardly in the grooves of the supports 9 and 10; and to maintain the forming fabrication in proper form or shape the stationary arm or element 21, pivoted in the brackets 22 and 23, sandwiches the forming fabrication between itself and the supporting plate 1 or the bed plate of the joining device, as well as between itself and the longitudinally extensive element 11. The forming fabrication slides easily between the stationary element 21 and one of the said plates and element 11 because of the permanent magnet 24, the bottom of which is secured to plate 1 and the top of which holds the stationary element 21 in proper spaced relation 55

and acts as a stop therefor, the said stationary element 21 or part thereof being made of magnetic material.

In some embodiments I have made one or both of the supports 9 or 10, from magnet material, which I then magnetized, so that there was a frictional drag between the said magnetized support or supports and the longitudinal element or component 11 as the component 11 slid on the said magnetized support or supports during the forming of the strip material fabrication, and this frictional drag helps to maintain the periphery of the forming fabrication against the gage 6.

As is easily comprehensive to those skilled in the art, the lateral grooves in the supports 9 and 10 are of sufficient height from the bottom thereof so that the sliding component 11 or the angular offset 13 secured thereto will not come into contact with the supporting plate 1 or the bed plate of the associated joining device; also the brackets 22 and 23 and the magnet 24 are of such size and adjustment that there is sufficient clearance between the component 11 and offset 13 and the stationary element 21 for the fabrication 17 to move freely during its formation.

It will also be understood that instead of the parts of applicant's device being assembled on a supporting plate 1 they may be secured directly to the bed plate of the cooperating joining device, and that various modifications may be made in the construction and arrangement of parts without departing from the spirit of the invention as claimed.

I claim:

1. In a device for forming fabrications from strip material, a supporting plate adapted to be aligned for use with a joining device, a magnet secured to the supporting plate, a movable component adapted to hold a nucleus for the joinder thereto of successive sections of strip material and to frictionally slide on the magnet during the joinder of successive sections of strip material to the nucleus, and a guide secured to the supporting plate adapted to maintain the unformed strip material in alignment for joinder by the joining device to the nucleus and forming fabrication, the said movable component being magnetizable.

2. In a device for forming fabrications from strip material, a supporting plate adapted to be aligned for use with a joining device, a component adapted to hold a nucleus for the joinder thereto of successive sections of strip material to form a fabrication, a guiding element secured to the supporting plate adapted to guide the component so that the component will move transversely of the line of feed of the strip material, a stationary element adapted to sandwich the forming fabrication between itself and the supporting plate as the component moves transversely and successive sections of strip material are joined to the nucleus thereon, and a magnet adapted to hold the stationary element at a pre-adjusted position, the said stationary element being magnetizable.

3. In a device for forming fabrications from strip material, a supporting plate adapted to be aligned for use with a joining device, a longitudinally extensive element adapted to slide on the guiding element parallel to the guiding element and to the supporting plate, a pivoted arm adapted to swing toward and away from the supporting plate and adapted to sandwich a forming fabrication between itself and the longitudi-

nally extensive element, and a stop adapted to maintain a fixed space between the pivoted arm and the longitudinally extensive element.

4. In a device for forming fabrications from strip material, a longitudinal element adapted to hold a nucleus for the joinder thereto of a section of strip material by a joining device, and a guiding element on which the longitudinal element is adapted to slide, one of the said elements being magnetized and the other of the said elements being magnetizable whereby there is a drag on the longitudinal element as it slides on the guiding element during the forming of a fabrication.

5. In a device for forming fabrications from strip material, a movable element adapted to hold a nucleus for the joinder thereto of successive sections of strip material, and a guiding element on which the movable element is adapted to slide, the said guiding element being positioned parallel to the path of movement of the said movable element, one of the said elements being magnetized and the other of the said elements being magnetizable whereby there is a drag on the movable element as it slides on the guiding element.

6. In a device for forming fabrications from strip material, a supporting base adapted to be aligned for use with a joining device, a magnetic guiding element secured to the supporting base at an angle that is transverse to the line of feed of the joining device, and a cooperating magnetizable component adapted to hold a nucleus for the joinder thereto of successive sections of strip material and adapted to slide on and to be magnetically attracted by the magnetic guiding element as successive sections of strip material are joined to the nucleus.

7. In a device for forming fabrications from strip material, a supporting base adapted to be aligned for use with a joining device, a movable element mounted on the supporting base and adapted to hold a nucleus for the joinder thereto of a section of strip material, a magnetizable pivoted arm adapted to swing toward and away from the supporting base and adapted to sandwich the nucleus and strip material fabrication between itself and the movable element, and a magnet adapted to hold the magnetizable pivoted arm, the said magnet being secured to the said supporting base.

8. In a device for forming fabrications from strip material, a support adapted to be aligned for use with a joining device, a guide on the support, and a substantially L-shaped structure having two legs, each of which is positioned at an angle with respect to the other, one of the said legs being adapted to slide horizontally in the guide parallel therewith and in a direction transversely of the line of feed of the joining device, and the other of the said legs being adapted to hold a nucleus for the joinder thereto of successive sections of strip material, said guide having its guiding surfaces directed in a direction transverse to the line of feed whereby the leg sliding therein will move transverse to the line of feed.

9. In a device for forming fabrications from strip material, a support adapted to be aligned for use with a joining device, a guide on the support, and a substantially L-shaped structure having a longer leg and a shorter leg each of which is positioned at an angle with respect to the other, the said longer leg being adapted to slide horizontally in the guide parallel therewith

and in a direction transversely of the line of feed of the joining device, and the said shorter leg being adapted to hold a nucleus for the joinder thereto of a strip of material, said guide having its guiding surfaces directed in a direction transverse to the line of feed whereby the leg sliding therein will move transverse to the line of feed.

10. In a device for forming fabrications from strip material, a support adapted to be aligned for use with a joining device, a guide positioned horizontally on the support and extending in a direction transverse to the line of feed of the joining device, and a longitudinally extensive element adapted to slide in the guide parallel to the guide and adapted to hold a nucleus for the joinder thereto of an independent strip of material, the said longitudinally extensive element being mounted in the guide and being adapted to slide therein.

11. In a device for forming fabrications from strip material, a support adapted to be aligned for use with a joining device, a guide positioned horizontally on the support and extending in a

direction transverse to the line of feed of the joining device, a longitudinally extensive element adapted to slide in the guide parallel to the guide, and a needle on the longitudinally extensive element adapted to support a rotating nucleus as successive sections of strip material are spirally joined thereto by a joining device, the said longitudinally extensive element being mounted in the guide and being adapted to slide therein.
